MAGNETIC FIXTURE FOR HOLDING WORK
TO BE GROUNDRichard G. Nill, Fort Wayne, Ind., assignor to
Fort Wayne Tool, Die and Engineering Com-
pany, Fort Wayne, Ind., a partnership

Application January 19, 1946, Serial No. 642,328

10 Claims. (Cl. 51—216)

1

This invention pertains to a fixture for holding work to be ground, and more particularly to a fixture for holding work, one edge of which is to be finished and shaped, or a fixture adapted for holding work to be straight ground.

It is an object of this invention to provide a fixture for positively holding work to be ground in such a manner that no scarring of the work can happen.

Another object of the invention is to provide a fixture for holding work to be operated upon, in a plurality of directions whereby the operating tool cannot move said work.

Another object of the invention is to provide a fixture for holding work to be operated upon in such a manner that a plurality of mating segments of the work can be operated upon at once and in a similar manner.

Another object of the invention is to provide a fixture for holding work to be operated upon whereby a shape such as back taper can be readily ground on a plurality of work members.

With these and various other objects in view, the invention may consist of certain novel features of construction and operation as will be more fully described and particularly pointed out in the specification, drawings and claims appended hereto.

In the drawings which illustrate embodiments of the device and wherein like reference characters are used to designate like parts—

Figure 1 is a fragmentary elevation of a fixture embodying the invention, shown particularly for holding a plurality of segments, the ends of which are to be ground;

Figure 2 is a top plan view of the fixture illustrated in Figure 1;

Figure 3 is an end elevation of the fixture illustrated in Figures 1 and 2;

Figure 4 is a top plan view of a pair of segments illustrating the grinding of back taper thereon;

Figure 5 is an elevation looking toward the ground end of the segments illustrated in Figure 4 showing the grinding of the back taper thereon;

Figure 6 is a top plan view of a modified form of fixture adapted particularly for grinding lamination punches;

Figure 7 is an end elevation of the fixture illustrated in Figure 6;

Figure 8 is a fragmentary end elevation of the fixture illustrated in Figures 6 and 7 showing the same with the end gauge bar removed; and,

Figure 9 is an end elevation, partly in section, of a modified form of fixture shown in Figures 6 to 8 inclusive.

2

Referring first of all, more particularly, to the fixture illustrated in Figures 1 to 3 inclusive, said fixture comprises the base 20 provided with securing means or member 22 for facilitating the securing of the fixture assembly in position with respect to an operating tool for the work held by the fixture, for example, a grinder. The base is provided with the work holder base 24 and with a magnetic power unit 26. The base 20 is secured as at 28 to the securing means 22 and the power unit is secured thereto as at 30 to the securing means 22 and as at 32 to one portion of the work holder base 24.

The work holder base 24 comprises two parts 15 or blocks 34 and 36 of magnetic material such as steel, said parts being bonded but insulated from each other by means of the brazed joint 38 of non-magnetic material, such as brass. The work holder base is secured as at 40 to the base 20, and 20 the work holder 42 is secured as at 44 and 46 to the work holder base 24, the securing means 46 also serving to secure in place the top gauge bars 48 of the adjacent work holding members 42.

25 The work holding members 42 comprise a pair of work holding blocks 50 and 52 of magnetic material such as steel, secured together but insulated by means of the brazed, non-magnetic joint 54, preferably of brass. The joints 54 and 38 are aligned and the joint 54 is preferably so disposed that it is slightly overlapped by means of the top gauge bar 48. The adjacent work holding blocks 50 and 52 (and consequently adjacent bars 48) are preferably angularly disposed 35 with respect to each other (Figure 1) so that when work with open edges is ground a desired back taper will be ground on the said work. The work contacting surfaces 56 of the adjacent blocks 50 are also sloped one with respect to the other 40 (Figures 2 and 3) so that a proper back taper is ground on the edges of the work held on the fixture.

45 End gauge bars 58 are disposed adjacent one side of each of the members 42 for engaging the ends of the work 60 held on the members 42 whereby they can be properly positioned. When the segments or work 60 are to be finished, as by grinding, each segment is disposed so that the two rear edges, that is, the edge not to be 50 ground, contact the edge of the adjacent gauge bar 48 (Figure 3) and one end of the said segments engages the adjacent end gauge bar 58 (Figure 2).

55 The power unit 26 is energized and magnetic flux passes from the power unit through mem-

ber 36, block 52, gauge bar 48, work 60, block 50, member 34, base 20, member 22, back to the power unit, all as shown by the arrows. Thus the work, that is, segment 60, is held both against the surface 56 and against the edge of the gauge bar 48. The segments are placed on the adjacent work holding members 42 with the tops of the segments adjacent to each other, as illustrated in Figure 4. The grinding tool can then be operated over the work properly grinding the open edge of the work and at the same time forming the open edge of the segment with the proper back taper, removing the metal as indicated by the dotted lines as at 62 in Figure 4, and removing metal along the free edge as shown by the dotted lines 64 in Figure 5. The segments can be reversed maintaining the tops together for grinding the opposite side of the edges thereof. It is, of course, understood that while only two adjacent work holding members 42 are shown, any number of sets (pairs) of these work holding members may be used on the fixture.

Referring now to the fixtures illustrated in Figures 6 to 8 inclusive, said fixtures comprise the base plate 66 provided with securing means 68 for conveniently fastening the fixture to a machine, such as a grinder. The base plate is provided with the work holder 70 having securing means 72, the end of the work holder 70 being provided with the end gauge bar 74 secured thereto as at 76. Both ends may be provided with said gauge bars, if desired. The work holder 70 is formed of spaced blocks 78 and 80 of magnetic material such as steel connected together by the brazed joint 82 of non-magnetic material, such as brass.

The base plate 66 is connected to the work holder 70 by means of the steel plate 84 (and securing means 72), and a power unit 86 is interposed between the base plate 66 and the block 80 of work holder 70. The work holding block 80 is provided with the top gauge bar 88, secured thereto as at 90, and is preferably of magnetic material such as steel. The fixture illustrated is adapted particularly for grinding punches, and blocks 80 and 78 are formed with the punch segment receiving recess 92 so shaped that the top of segment 94 is presented properly to the grinding wheel.

The punch segment 94 is disposed in the recess and overlies the brazed, non-magnetic joint 82 (Figure 8), one edge 95 of the punch abutting the adjacent edge 97 of the top gauge bar 88. When the power unit 86 is energized, magnetic flux will flow from said unit through the block 80, through gauge bar 88, through work 94, block 78, plate 84, base plate 66, and to the power unit 86, whereby the segment 94 is held in a downward direction against blocks 78 and 80. It is, of course, understood that the segments may be positioned longitudinally of the fixture by abutting the end gauge bar 74.

In Figure 9 is shown a fixture having a base 96 corresponding to base 66, the base being provided with a support 98, corresponding to support 84 interposed between the base, and the work holder 100, corresponding to work holder 70. As before, the work holder shown is for a punch segment where only a straight cut or straight grinding operation is performed, and the work holder is properly shaped to present the work to the grinding wheel in the manner desired. A power unit 102 is interposed between the base 96 and the work holder 100. It is un-

derstood that an end gauge bar (not shown) or gauge bars, similar to gauge bar 74, may be used and a top gauge bar 104 is secured to the work holding block 106 of the work holder 100. Block 106 is separated from block 108 of the work holder by the brazed, non-magnetic joint 110, preferably of brass, and as before, members 96, 98, 108, 104 and 106 are of magnetic material, such as steel.

In this modification the gauge bar is so disposed that it slightly overlaps the non-magnetic joint 100 and the edge of the gauge bar abuts and positions the work 112 by engagement with an edge thereof. When the work 112 is supported, one edge thereof slightly overlaps the brazed joint and when the power unit is energized, magnetic flux passes from the power unit 102, through block 106, gauge bar 104, work 112, block 108, support 98 and through base 96 back to the power unit, as shown by the arrows whereby the work is held both downwardly and edgewise, thus preventing any tendency of operating tool, such as the grinding wheel, from laterally moving the work.

It is to be understood that this application is not to be limited by the exact embodiments of the device shown, which are merely by way of illustration and not limitation as various and other forms of the device will, of course, be apparent to those skilled in the art without departing from the spirit of the invention or the scope of the claims.

I claim:

1. In a fixture, the combination of a base of magnetic material, a support of magnetic material disposed on said base, a work holder base disposed on said support, said work holder base and support being adapted to be magnetically connected to a magnetic power unit, said work holder base comprising a plurality of blocks of magnetic material separated but joined by non-magnetic material, one of said blocks being magnetically connected to said power unit and the other being magnetically connected to said support, a work holder supported on said work holder base and comprising spaced blocks of magnetic material, one of said blocks being magnetically connected to one of said first named blocks and the other of said blocks being magnetically connected to the other of said first named blocks, the blocks of said work holder being separated but connected by non-magnetic material aligned with and contacting the other non-magnetic material, an end gauge bar on said work holder blocks, and a top gauge bar of magnetic material secured to one of the work holder blocks and having an edge overlapping the non-magnetic material but spaced from the other work holder block, said work holder being adapted to receive metallic work so disposed on the work holder block which is spaced from the top gauge bar and overlying the non-magnetic material to engage said top gauge bar whereby when said power unit is energized, magnetic flux passes through one of the work holder base blocks, one of the work holder blocks, top gauge bar, work, the other of the work holder blocks, the support, and the base, back to the power unit to magnetically fixedly secure said work to said fixture.

2. In a fixture, the combination of a base of magnetic material, a support of magnetic material disposed on said base, a work holder supported by said support and comprising spaced blocks of magnetic material, said work holder

base and support being adapted to be magnetically connected to a magnetic power unit, one of said blocks being magnetically connected to said power unit, and the other of said blocks being magnetically connected to said support, the blocks of said work holder being separated but connected by non-magnetic material and a top gauge bar of magnetic material secured to one of the work holder blocks and having an edge overlapping the non-magnetic material but spaced from the other work holder block, said work holder being adapted to receive metallic work so disposed on the work holder block which is spaced from the top gauge bar and overlying the non-magnetic material to engage said top gauge bar whereby when said power unit is energized, magnetic flux passes through said power unit, work holder blocks, top gauge bar, work and support to fixedly secure said work to said fixture.

3. In a fixture, the combination of a base of magnetic material, a support of magnetic material disposed on said base, a work holder base disposed on said support, said work holder base and support being adapted to be magnetically connected to a magnetic power unit, said work holder base comprising a plurality of blocks of magnetic material separated but joined by non-magnetic material, one of said blocks being magnetically connected to said power unit and the other being magnetically connected to said support, a work holder supported on said work holder base and comprising spaced blocks of magnetic material, one of said blocks being magnetically connected to one of said first named blocks and the other of said blocks being magnetically connected to the other of said first named blocks, the blocks of said work holder being separated but connected by non-magnetic material aligned with and contacting the other non-magnetic material, and a top gauge bar of magnetic material secured to one of the work holder blocks and having an edge overlapping the non-magnetic material but spaced from the other work holder block, said work holder being adapted to receive metallic work so disposed on the work holder block which is spaced from the top gauge bar and overlying the non-magnetic material to engage said top gauge bar whereby when said power unit is energized, magnetic flux passes through one of the work holder base blocks, one of the work holder blocks, top gauge bar, work, the other of the work holder blocks, the other of the work holder base blocks, the support, and the base, back to the power unit to fixedly secure said work to said fixture.

4. In a fixture, the combination of a base of magnetic material, a support of magnetic material disposed on said base, a work holder supported by said support and comprising spaced blocks of magnetic material, said work holder base and support being adapted to be magnetically connected to a magnetic power unit, one of said blocks being magnetically connected to said power unit, and the other of said blocks being magnetically connected to said support, the blocks of said work holder being separated but connected by non-magnetic material, an end gauge bar on said work holder blocks, and a top gauge bar of magnetic material secured to one of the work holder blocks and having an edge overlapping the non-magnetic material but spaced from the other work holder block, said work holder being adapted to receive metallic work so disposed on the work holder block which is spaced from the top gauge bar and overlying the non-magnetic material to

engage said top gauge bar whereby when said power unit is energized, magnetic flux passes through said power unit, work holder blocks, top gauge bar, work and support to fixedly secure said work to said fixture.

5. In a fixture, the combination of a base of magnetic material, a support of magnetic material disposed on said base, a work holder base disposed on said support, said work holder base and support being adapted to be magnetically connected to a magnetic power unit, said work holder base comprising a plurality of blocks of magnetic material separated but joined by non-magnetic material, one of said blocks being magnetically connected to said power unit and the other being magnetically connected to said support, a pair of work holders supported on said work holder base and disposed in predetermined relation to each other, each of said work holders comprising spaced blocks of magnetic material, one of said blocks being magnetically connected to one of said first named blocks and the other of said blocks being magnetically connected to the other of said first named blocks, the blocks of each of said work holders being separated but connected by non-magnetic material aligned with and contacting the other non-magnetic material, an end gauge bar for each work holder, and a top gauge bar of magnetic material for each work holder secured to one of the work holder blocks of each holder and having an edge overlapping the non-magnetic material but spaced from the other work holder block, said work holders being adapted to receive metallic work so disposed on the work holder block spaced from the top gauge bar and overlying the non-magnetic material to engage said top gauge bar whereby when said power unit is energized, magnetic flux passes through said blocks, work, support and base, back to the power unit to fixedly secure said work to said fixture.

6. In a fixture, the combination of a base of magnetic material, a support of magnetic material disposed on said base, a work holder base disposed on said support, said work holder base and support being adapted to be magnetically connected to a magnetic power unit, said work holder base comprising a plurality of blocks of magnetic material separated but joined by non-magnetic material, one of said blocks being magnetically connected to said power unit and the other being magnetically connected to said support, a pair of work holders supported on said work holder base and disposed in predetermined relation to each other, each of said work holders comprising spaced blocks of magnetic material, one of said blocks being magnetically connected to one of said first named blocks and the other of said blocks being magnetically connected to the other of said first named blocks, the blocks of each of said work holders being separated but connected by non-magnetic material aligned with and contacting the other non-magnetic material, and a top gauge bar of magnetic material for each work holder secured to one of the work holder blocks of each holder and having an edge overlapping the non-magnetic material but spaced from the other work holder block, said work holders being adapted to receive metallic work so disposed on the work holder block spaced from the top gauge bar and overlying the non-magnetic material to engage said top gauge bar whereby when said power unit is energized, magnetic flux passes through said blocks, work, sup-

port and base, back to the power unit to fixedly secure said work to said fixture.

7. In a fixture, the combination of a base of magnetic material, a support of magnetic material disposed on said base, a pair of work holders supported by said support and disposed in predetermined relation to each other, said support and work holders being adapted to be magnetically connected to a magnetic power unit, each of said work holders comprising spaced blocks of magnetic material, one of said blocks being magnetically connected to one of said first named blocks and the other of said blocks being magnetically connected to the other of said first named blocks, the blocks of each of said work holders being separated but connected by non-magnetic material, an end gauge bar for each work holder, and a top gauge bar of magnetic material for each work holder secured to one of the work holder blocks of each holder and having an edge overlapping the non-magnetic material but spaced from the other work holder block, said work holders being adapted to receive metallic work so disposed on the work holder block spaced from the top gauge bar and overlying the non-magnetic material to engage said top gauge bar whereby when said power unit is energized, magnetic flux passes through said blocks, work, support and base, back to the power unit to fixedly secure said work to said fixture.

8. In a fixture, the combination of a base of magnetic material, a support of magnetic material disposed on said base, a pair of work holders supported by said support and disposed in predetermined relation to each other, said support and work holders being adapted to be magnetically connected to a magnetic power unit, each of said work holders comprising spaced blocks of magnetic material, one of said blocks being magnetically connected to one of said first named blocks and the other of said blocks being magnetically connected to the other of said first named blocks, the blocks of each of said work holders being separated but, connected by non-magnetic material, and a top gauge bar of magnetic material for each work holder secured to one of the work holder blocks of each holder and having an edge overlapping the non-magnetic material but spaced from the other work holder block, said work holders adapted to receive metallic work so being disposed on the work holder block spaced from the top gauge bar and overlying the non-magnetic material to engage said top gauge bar whereby when said power unit is energized, magnetic flux passes through said blocks, work, support and base, back to the power unit to fixedly secure said work to said fixture.

9. In a fixture, the combination of a base of magnetic material, a support of magnetic material disposed on said base, a work holder supported by said support and comprising spaced blocks of magnetic material, said work holder base and support being adapted to be magnetically connected to a magnetic power unit, one of said blocks being magnetically connected to said power unit, and the other of said blocks being magnetically connected to said support, the blocks of said work holder being separated but connected by non-magnetic material and a top gauge bar secured to one of the work holder blocks and having a work engaging edge spaced from the non-magnetic material, said work holder being adapted to receive metallic work so disposed on the work holder block which is spaced from the top gauge bar and overlying the non-magnetic material to engage said top gauge bar whereby when said power unit is energized, magnetic flux passes through said blocks, work support, base, back to the power unit to fixedly secure said work to said fixture.

10. In a fixture, the combination of a base of magnetic material, a support of magnetic material disposed on said base, a work holder supported by said support and comprising spaced blocks of magnetic material, said work holder base and support being adapted to be magnetically connected to a magnetic power unit, one of said blocks being magnetically connected to said power unit, and the other of said blocks being magnetically connected to said support, the blocks of said work holder being separated but connected by non-magnetic material, an end gauge bar provided on said blocks and a top gauge bar secured to one of the work holder blocks and having a work engaging edge spaced from the non-magnetic material, said work holder being adapted to receive metallic work so disposed on the work holder block which is spaced from the top gauge bar and overlying the non-magnetic material to engage said top gauge bar whereby when said power unit is energized, magnetic flux passes through said blocks, work support, base, back to the power unit to fixedly secure said work to said fixture.
